CLAIM

The ornamental design for a foot peg mount for a motorcycle, as shown and described.

DESCRIPTION

FIG. 1 is a front right perspective view of a foot peg mount for a motorcycle showing our new design; a front left perspective view appears as a mirror image of the front right perspective view;

FIG. 2 is a front elevational view thereof;

FIG. 3 is a back elevational view thereof;

FIG. 4 is a top plan view thereof;

FIG. 5 is a bottom plan view thereof; and,

FIG. 6 is a front and right side perspective view thereof.

The broken line portions are environmental structuring and form no part of the claimed design.
